UNITED STATES PATENT OFFICE.

EPHRAIM JAMES CLARK, OF SEATTLE, WASHINGTON.

FEATHERING PADDLE WHEEL.

Application filed November 15, 1926. Serial No. 148,461.

My invention relates to an improvement in feathering paddle wheels.

It is an object to provide a paddle wheel, for the use of vessels, of the type wherein the blades are moved through a quarter revolution on their own individual axes at the commencement of a forward movement, that is, at the top of their stroke, and again turned through a quarter revolution into working position at the beginning of a power or backward stroke.

Among the objects of the present invention, as related to this type of paddle wheel, are: The provision of means for continuing rotation of the individual paddles in a single direction, as distinguished from oscillation; the employment of simple means for effecting this rotation by quarter turn intervals and at the proper time in the revolution of the paddle wheel; the provision of simple means to hold the paddle either in working position or in feathering position, except at such times as it is in process of changing from one position to the other; the provision of a construction whereby single paddles and associated parts may be removed or inspected with the minimum removal of parts and without disturbance of other paddles; the provision of a simple assembly for the individual paddles and associated parts, whereby all are securely and rigidly connected, yet may be disassembled in a short time and with little effort.

A further object is the general simplification and improvement in details of construction of such a feathering paddle wheel.

My invention comprises the novel parts and the novel assembly of such parts as shown in the accompanying drawings, as described in the specification, and as more particularly defined in the claims terminating the same.

In the accompanying drawings I have shown my invention in a form which is now preferred by me, it being understood, however, that variations may be made from the details shown in these drawings within the spirit of the present invention.

Figure 1 is an elevation of the paddle wheel, showing the parts in the position they would assume during a change of one of the paddle wheels from feathering into working position, with parts of the fixed cam shown in section;

Figure 2 is a section substantially on the line 2—2 of Figure 1;

Figure 3 is a section on line 3—3 of Figure 1;

Figure 4 is a perspective view, showing the manner in which one of the paddles and its associated parts can be disassembled.

The paddle wheel comprises a rotative hub, indicated in general by the numeral 1, from which radiate a plurality of paddles 2. The hub is mounted upon a shaft 3 supported in suitable bearings 30 and rotated from a source of power, as by means of the bevel gears 31 and 32, or by any other suitable means.

The individual paddles 2 are so supported in the hub 1 that they may rotate, each on its individual axis, which axis preferably extends radially of the hub 1. Preferably, also, all of the paddles 2 are rotated on axes which lie in a common plane.

As is best seen in Figure 4, the paddle assembly includes and is centered upon a post 4, which at least at its inner end is rounded, as indicated at 40, to be received in a journal bearing 12 in the pivot block, and which carries a thrust bearing or footing 41, shown as an enlarged head on the post. The post 4 is slotted, as is indicated at 42, from its outer end inward, and its outer end may be squared.

Fitting upon the post 4 are in turn a guide block 5, a cam block 6, and the separable paddle 2. The guide block 5 has squared sides 50, and an aperture 51, which receives the post 4. If the post 4 is squared, the aperture 51 is likewise squared, or is otherwise arranged to rotate with the post 4. The cam block 6, outward of the guide block, has recesses 60 for the engagement of fixed cams 7 and 70, which will be hereinafter described, and having an aperture 61 receiving the post 4 and, like the post, squared. To further secure the cam block 6 and the guide block 5 together, and to prevent rotative movement of one relative to the other, the guide block may be provided with a transverse groove 52 in its outer face, and the cam block 6 may have a transverse rib or key 63 adapted to be received in the groove 52. Obviously, the cam block and the guide block might be formed integral, but for convenience of construction and assembly, it is preferred to form them separately.

Outward of the cam block 6 is disposed the paddle 2. This is received in the slot 42 of the post and, preferably also, is provided with guides 20 embracing the two legs

of the post to further support and secure the paddle. The inner edge 23 of the paddle may be received in a transverse groove 62 in the outer face of the cam block 6. By these means the guide block 5, the cam block 6 and the paddle 2 may all be firmly and rigidly assembled as a unit, together with the post 4, and this assembly is simply locked together by means of pins or bolts 22 receivable in registering holes in the post and in the paddle, as, for example, the holes 43.

Each paddle is thus a complete unit provided with its guide block and cam block, and to assemble these into the paddle wheel the rotative hub is formed of a plurality of members. If four paddles are employed, the hub will be formed of four members. These members are formed as two halves divided along a plane normal to the axis of the rotative hub and including the axes of all of the paddles, each half being again divided, along a plane including the axis of the paddle and the axes of two diametrically opposite paddles into quarters 1^a, 1^b, 1^c, and 1^d. These quarters, however, are so disposed that their planes of division are at right angles, thus, as seen best in Figure 2, a single quarter of the hub may be removed to expose the journal bearing 12 for a single paddle merely by the removal of two of the bolts 11 which hold the hub members together. The removal of this quarter of the rotative hub does not disturb the remaining three paddles.

Adjacent the path of movement of the paddles, and more especially adjacent the path of the cam blocks 6, fixed cams 7 and 70 are positioned. These cams are arranged to engage in the cam recesses 60 as the paddles pass. One of these cams, 7, for example, is arranged to throw the paddles into working position, and the other cam, 70, is arranged to throw the paddles into feathering position. Obviously, these two cams are substantially diametrically opposite, but I prefer that they be not precisely 180° apart, but that they be so arranged that one cam, the cam 7 preferably, will throw a paddle into working position slightly in advance of action of the cam 70 to throw another paddle into feathering position. Thus, as is best seen in Figure 2, there are always at least two paddles in working position, with a third moving into working position. A further advantage of thus arranging the cams 7 and 70 is the avoidance of the excessive shock to the mechanism which would be caused by the simultaneous engagement of two cam blocks 6 with both fixed cams 7 and 70.

Either the fixed or the rotative cams may be so mounted as to lessen the shock due to such contact, and to this end, and as seen in Figure 1, I have provided the cam 7 with guide ribs 71 receivable in a guide recess 73 and backed by resilient bumpers 74, which

may be of rubber or like material. The shock of engagement of the cam blocks 6 is thus taken by the rubber bumpers 74. This entire assembly is preferably supported in a removable section 75 supported in a plate 76. This plate 76 serves a further function, in that the faces 50 of the guide blocks 5 engage it to prevent twisting of the paddles on their axes, except as they may be turned by the fixed cams 7 or 70. During such turning, the corners of guide blocks 5 must be received in recesses 77 provided in the face of a plate 76 for this purpose. The plate 76, it will be understood, is secured to or forms a part of the frame which supports the paddle wheel, as for example, the frame 78.

It will now be obvious that as the paddle wheel is rotated, the individual cam blocks 6 engage in turn the fixed cams 7 and 70, and upon engagement with the cam 7 for example, are turned into working position, and after having completed substantially a half revolution of the paddle wheel, the same cam block engages the fixed cam 70 and is moved into feathering position. Further, this movement is continuously in a given direction about the individual axes of the paddles, and is not an oscillatory movement; thus wear is equally distributed throughout the bearings of the individual paddles and the device will continue to function over long periods without adjustment or repair.

What I claim as my invention is:

1. A feathering paddle wheel comprising a rotative hub, a plurality of paddles radiating from said hub and each journaled in said hub for rotation about an axis extending radially of the hub, a quadrangular cam secured to and rotative with each paddle, and having a notch entering each corner, a fixed cam engageable with a notch of each of said rotative cams in turn, as the paddles corresponding to the respective rotative cams reach the end of their power stroke, to turn said paddles through a quarter revolution into feathering position, and a second fixed cam also engageable in turn with a succeeding notch in the said rotative cams, as the corresponding feathering paddles reach a position corresponding to the start of a power stroke, to turn said paddles in the same direction as the first fixed cam, and through a quarter revolution, into working position.

2. A feathering paddle wheel as in claim 1, wherein the second fixed cam is spaced less than 180° from the first fixed cam, whereby at least half of said paddles are at all times in working position.

3. A feathering paddle wheel comprising four radially disposed paddles each rotatable on its individual axis independently of the other paddles, means for rotating said paddles each on its own axis to feather the forwardly moving paddle, and a rotative hub

- supporting and forming journals for said paddles, said hub being divided along a plane transverse to its own axis and including the axes of all of said paddles, and these 5 halves being again divided into two quarters along planes including the axes of two diametrically opposite paddles and the axis of the hub, the planes of division of the two quarters of the complementary halves being 10 at right angles, whereby upon removal of any quarter of the hub a single paddle may be removed from its journal in the hub.
4. In a paddle wheel, a post adapted at its inner end to be received and to rotate 15 in a journal bearing, and slotted from its outer end inwards, a paddle grooved on opposite sides to receive the arms of said slotted post, thereby to be interlockingly engaged and supported by said post, and means 20 for maintaining said paddle and post in engagement.
5. In a paddle wheel, a post adapted at its inner end to be received and to rotate in a journal bearing, and slotted from its outer 25 end inwards, a cam block secured upon said post adjacent its inner end, and transversely grooved across its outer face, a paddle received in the slot in said post, and having its inner edge received in said groove in the 30 cam block, and means for preventing separation of said paddles, said cam block, and said post.
6. A paddle for paddle wheels as in claim 5, and an apertured guide block non-rotatively mounted upon said post inwardly of 35 the cam block, said guide block being transversely grooved across its outer face, and the cam block having a transverse key projecting from its inner face and receivable in said groove in the guide block, the several 40 elements being held against separation by means of pins passing through the post and the paddle, whereby upon removal of said pins, the entire paddle may be disassembled.
7. A feathering paddle wheel comprising 45 a rotative hub, a plurality of paddles radiating from said hub and each journaled in said hub for rotative movement about an axis extending substantially radially of the hub, a cam secured to and rotative with each 50 paddle, a fixed plate having a pair of notches in its opposite edges, a sliding filler section receivable in each of said notches, a fixed cam removably and yieldably supported in each of said filler sections, the fixed cams, 55 filler plate and the plate supporting them being positioned adjacent the path of said rotative cams, to be engaged thereby, but each filler plate being accessible for removal independently of the other and of the rotative cams and paddles.

Signed at Seattle, King County, Washington, this 30th day of October, 1926.

EPHRAIM JAMES CLARK.
